UNITED STATES PATENT OFFICE

JOHN R. ROGERS, OF BROOKLYN, NEW YORK, ASSIGNOR TO MERGENTHALER LINOTYPE COMPANY, A CORPORATION OF NEW YORK

TYPOGRAPHICAL MACHINE

Application filed April 20, 1929. Serial No. 356,677.

This invention relates to typographical machines, such as linotype machines of the general organization represented in Letters Patent No. 436,532 to O. Mergenthaler, wherein circulating matrices are released from a magazine in the order in which their characters are to appear in print and then assembled in line, the composed line transferred to the face of a mold, the mold filled 10 with molten metal to form a slug or linotype against the matrices which produce the type characters thereon, and the matrices thereafter elevated and returned through distributing mechanism to the magazine from which 15 they are started. More particularly, it relates to machines equipped with a plurality of magazines containing matrices of different fonts and arranged in constant operative relation to a corresponding plurality of distributors so that distribution of the matrices 20 into all the magazines may be carried on simultaneously.

In some of the commercial machines of this class, the magazines are pivotally mounted in 25 such manner that any selected one thereof may be swung into operative relation to a single or common set of assembling devices without disturbing their operative connection with the distributing mechanism. For 30 example, in the machine shown in the Kennedy Patent No. 1,705,977 dated March 19, 1929, the several magazines are mounted to turn about independent axes located below and close up to the respective distributors so 35 that the intermediate magazine entrances (which conduct the matrices from the distributors to the magazines) will constantly maintain their operative relation to the distributors, it being noted that in this particular machine the distributing mechanism embodies a plurality of character distributors arranged one above another and each comprising a toothed bar and a distinct set of matrix conveying screws, together with a 40 font separator arranged in line with the upper character distributor and which serves to direct matrices of one font directly onto the upper distributor bar and to deliver matrices of the other fonts to the lower distributor 45 bar.

In this prior patented arrangement, however, it will be observed that the upper magazine entrance is used to conduct the matrices from the lower distributor to the upper magazine, while the lower magazine 55 entrance is employed to conduct the matrices from the upper distributor to the lower magazine. With such an arrangement, certain disadvantages arise: For instance, when it is desired to gain access to the upper magazine or the upper magazine entrance, it is 60 first necessary to swing the lower magazine entrance out of the way; furthermore, the lower magazine entrance has to be made of considerable length in order to reach from 65 the upper distributor to the lower magazine; and, in addition, the matrices stored in the upper magazine, which is the one more frequently removed, are required to be notched 70 in order to be distributed into that magazine 75 by the lower distributor.

The present invention is directed primarily to a machine of the class shown and described in the said Kennedy patent, but contemplates certain improvements which are intended to obviate the disadvantages above mentioned, as well as others unnecessary to refer to. To this end, it is proposed to arrange the magazine entrances so that the upper one will serve to conduct matrices 80 from the upper distributor to the upper magazine, while the lower one will serve to conduct matrices from the lower distributor to the lower magazine, whereby both entrances may be made of comparatively short 85 length, as is desirable, and whereby matrices stored in the upper magazine (since they are distributed into that magazine by the upper distributor) may be free from font distinguishing notches, thus enabling the larger 90 size or display fonts, which are usually devoid of such font distinguishing notches, to be stored in the upper magazine for ready interchange.

In carrying out the invention, the two magazine entrances are separately pivoted in such manner that either may be swung rearwardly and downwardly to give access to the interior parts without disturbing the other, and this notwithstanding the superposed re- 95 100

lation of the two character distributors. In the specific embodiment illustrated, the lower magazine entrance is pivoted at a point below the upper end of the lower magazine, as ordinarily, while the upper magazine entrance is pivoted at a point located at a considerable distance rearward of the upper magazine, and clear of the lower magazine entrance, and in such position that it (the upper magazine entrance) may be moved bodily in a rearward direction from its operative position through the space between the two character distributors.

According to another feature of the invention, the superposed magazines, as well as their magazine entrances, are mounted in a common shift frame which is adapted to be swung about a movable axis located to the rear of and at a level intermediate the levels of the two character distributors or in such position that either selected magazine may be brought into operative relation to the fixed assembling devices without moving the upper ends of the magazine entrances out of matrix receiving relation to the overlying distributors.

The foregoing description has been given with reference to the main magazines and the associated parts, but in the present instance it is also proposed to employ auxiliary magazines arranged at the side of the main magazines or in tandem thereto. These auxiliary magazines, like the main magazines, are mounted for swinging movement so that any selected one may be brought into operative relation to the fixed assembling devices, (which are extended for the purpose), altho the auxiliary magazines are separately pivoted rather than carried in a common pivoted shift frame. The magazine entrances for the auxiliary magazines, however, are mounted in practically the same way as those for the main magazines, except that the upper entrance is pivoted directly to the fixed machine frame, while the lower entrance is pivoted directly to the lower magazine base frame. The matrices are distributed into the auxiliary magazines in the customary way, namely, by extending the character distributors sufficiently to the right to drop the matrices into the auxiliary magazine entrances.

A further feature of the invention has to do with the stoppage of the distributing mechanism when any one of the magazine entrances (whether main or auxiliary) is swung rearwardly from its operative position. In the embodiment illustrated, this is accomplished by mounting a part of the clutch controlling connections on each of the magazine entrances, such that when any entrance is swung rearwardly from its operative position, the train of connections will be broken and the clutch thereby disengaged to

arrest the operation of the distributing mechanism as a whole.

While the invention has herein been illustrated as applied to a particular class of machines, it should be understood that it is equally applicable to other kinds of machines as well. While, too, the invention has been illustrated in connection with a machine embodying only two main magazines and two auxiliary magazines, it is not intended to be so limited in its application, as a greater number of magazines might be employed if desired. These and other modifications and adaptations will readily suggest themselves to those skilled in the art, and it should therefore be understood that the invention is not limited to any particular form or embodiment except in so far as such limitations are specified in the claims.

Referring to the drawings:

Fig. 1 is a side elevation of a linotype machine equipped with the present improvements, the auxiliary magazines being removed;

Fig. 2 is a vertical section taken on the line 2—2 of Fig. 4;

Fig. 3 is a similar view, showing the upper auxiliary magazine entrance swung to the rear;

Fig. 4 is a rear elevation of the distributing mechanism;

Fig. 5 is a horizontal section taken on the line 5—5 of Fig. 4;

Fig. 6 is a view similar to Fig. 5, showing the distributor clutch released by the lower main magazine entrance; and

Fig. 7 is a vertical section taken on the line 7—7 of Fig. 4.

The matrices X are stored according to font or set in the two tandem series of superposed inclined magazines A, A', there being two magazines shown in each series, altho a greater number may be employed if desired. The main magazines A are of standard trapezoidal form and ordinarily contain the regular fonts used for the composition of straight work or body matter, while the auxiliary or supplementary magazines A' are of rectangular form and ordinarily contain the thicker matrix fonts used for the composition of heads and display matter, etc. The magazines A, A', are mounted on separate base frames A², A³, respectively, and those of each series, as will later be described, are mounted so that they may be swung upwardly and downwardly in the machine frame to locate either magazine in operative relation to the fixed assembler throat or raceway B. The magazines, as usual, are provided with escapements C, which control the release of the matrices therefrom and which are adapted to be actuated (when the selected magazines are in operative position) by a series of pivoted levers C¹, the latter being operated in the customary way from a keyboard (not

shown) through vertical reeds C². After assemblage and casting, the matrices are carried upward and delivered to the distributing mechanism, which first assorts them according to font and then releases them according to character, so that they may be returned through one or another of the channeled magazine entrances D¹, D², D³ and D⁴, to the magazine from which they started. The entrances D¹, D², connect the two main magazines A with the distributing mechanism, while the entrances D³, D⁴, connect the auxiliary magazines A¹ therewith.

As best shown in Fig. 3, the distributing mechanism includes the two character distributors E, E¹, arranged one directly above the other, and a font separator F located at the entrance to the upper distributor E. Each of the character distributors comprises, as usual, a longitudinally ribbed or toothed bar for releasing the matrices at different points according to character, and a distinct set of constantly driven conveying screws for propelling the matrices along the bar. The font separator F may be the same as that shown and described in the Kennedy patent before referred to and is intended, by means of the selecting bridge F¹, to support matrices belonging to one font until they become engaged by the upper distributor bar, and to permit those of other fonts to seek a slightly lower level and thus escape the bar. Matrices to be handled by the upper distributor may, therefore, be plain or solid at their bottom edges so as to receive support from the bridge F¹ (or if notched, have their notches located out of register with the transverse rib f of the bridge), while those intended for the lower distributor E¹ should have a notch located to correspond to that of the rib f (see Fig. 3). The notched matrices fall astride the rib f and are advanced by the upper distributor screws across short rail sections F² which drop them into a chute F³ leading to a lower distributor box (not shown) arranged at the entrance to the lower distributor. From this box, the notched matrices are fed one after another into the threads of the lower distributor screws which carry them along the associated bar for final distribution.

The matrix conveying screws of both distributors are driven constantly and in the usual way from the so-called intermediate shaft G (shown only in Fig. 1) through the medium of a disc clutch G¹ (Figs. 4, 5 and 6), which is splined to a short horizontal shaft G² and held resiliently engaged with a loose driving pulley G³ connected by a pulley band (not shown) to the intermediate shaft. The shaft G² is journaled in fixed bearings at the extreme right of the machine (at the left in the drawings) and is provided near one end with a gear G⁴ for driving the screws of the lower distributor E¹. Near its opposite end, the shaft G² is provided with a sprocket wheel

G⁵ for driving the screws of the upper distributor E, it being observed (see Fig. 4) that the spindle of one of these screws is extended through its bearing and provided with a corresponding sprocket wheel G⁶, which is aligned with the sprocket G⁵ and connected thereto by a chain G⁷.

The disengagement of the clutch G¹ from the drive pulley G³ is effected automatically by an over-balanced trip finger G⁸, which, in the present instance, is held in its inactive position (see Fig. 4) by a small bell-crank lever J pivoted at j to the framework and operable by a train of connections later to be described. The trip finger G⁸ is hinged on a horizontal axis g and when released is adapted to be projected (as shown in Fig. 7) into the path of a constantly rotating toothed cam G⁹ carried by the clutch G¹, whereby the clutch is withdrawn axially away from the pulley G³ and the driving connection between the latter and the shaft G² instantly broken. This operation stops the entire distributing mechanism, which may be restarted by withdrawing the finger G⁸ from engagement with the cam G⁹, either automatically as later described, or manually by means of a hand wheel G¹⁰ mounted on the outer end of the shaft G².

As best shown in Figs. 1 and 2 the entrances D¹ and D³ for the upper main magazine A and the upper auxiliary magazine A¹, respectively, are arranged in front of the lower distributor E¹ and are so mounted that they may be moved bodily rearward between the distributors when it is desired to gain access to the interior parts, and this without disturbing the lower magazine entrances D² and D⁴. The upper main magazine entrance D¹ (see Fig. 4) is supported by a pair of depending arms D⁵ pivoted at their lower ends, as at d⁵, to rigid extensions A⁴ which rise from the upper end of the lower main magazine base frame A² at the opposite sides thereof; and the upper auxiliary entrance D³ is similarly supported by a pair of depending arms D⁶, D⁷, which are pivoted respectively, as at d⁶ and d⁷, to fixed brackets O¹, O², secured to the distributor frame O. It is pointed out that the pivotal axes of these upper magazine entrances are so located (at the rear of the lower distributor E¹) and the shape of the entrances is such that they may be swung freely back and forth between the two distributors E, E¹ from and to their operative position.

In order to locate the entrances D¹ and D³ in proper relation to the upper distributor E and the magazines associated therewith, they are provided with suitable stop screws d, d¹, the former being mounted in offset portions of the depending arms D⁵ of the main entrance D¹ and arranged to bank against shoulders formed on the bracket extensions A⁴, and the latter being similarly mounted in

the respective arms D^6 , D^7 of the auxiliary entrance D^3 and arranged to bank against the lower distributor bar. In this connection, it may be observed that these entrances and their supporting frames (see Figs. 1 and 3) are disposed well forwardly of their pivotal axes and, consequently, their weight is sufficient to maintain them in their operative position without other means of support. As the entrances are swung rearwardly, however, they are caused gradually to change their position until finally inverted (see Fig. 3), and to catch any matrices that might at the time be lodged in one or more of the channels, each of said entrances is provided with a weighted tray D^8 , which is suspended from a pair of small bracket arms D^9 secured to the entrance supporting frame and projecting upwardly from the opposite ends thereof.

The lower main magazine entrance D^2 is pivoted or hinged at its opposite sides to the rigid extensions A^4 of the lower magazine base frame A^2 in such manner that it may be swung rearwardly and downwardly at will from its operative position, without interference with the upper magazine entrance D^1 . In this case, however, due to the location of its pivotal axis, the entrance D^2 must be sustained in its operative position, and hence there is provided (see Fig. 4) a pair of short retaining arms or fingers O^3 journaled on a fixed horizontal rod O^4 and arranged respectively adjacent the inner face of the extensions A^4 . These arms O^3 are held under the tension or torsion springs O^5 , coiled around the rod O^4 , against anti-friction rollers d^2 carried at the opposite sides of the entrance and they are not only intended to hold the entrance resiliently in its operative position, but also serve to counterbalance the weight of the same as it is swung to and fro. The entrance D^2 is also provided with adjustable stop screws d^3 , which (as shown in Figs. 1 and 4) are adapted to engage the lower edge of the extensions A^4 when the entrance is swung upwardly into operative position.

The lower auxiliary magazine entrance D^4 is pivoted directly to the lower magazine base frame A^3 in a manner similar to that of the entrance D^2 , but, being comparatively light, it is sustained resiliently in its raised position by an ordinary pull spring D^{10} anchored to the fixed frame-bracket O^2 . Set screws d^4 , carried by the entrance frame and engaging the upper end of the lower magazine base frame A^3 , are also provided to locate the entrance in proper relation to the distributor E^1 and the lower auxiliary magazine A' .

For reasons later to appear, the two lower magazine entrances D^2 and D^4 are provided respectively with angular bracket members J^1 and J^2 extending upwardly therefrom behind the lower distributor E^1 ; and the two upper magazine entrances D^1 and D^3 are pro-

vided respectively with corresponding fixed depending members J^3 and J^4 , the depending member J^3 of the main magazine entrance D^1 being located adjacent the upper end of the bracket member J^1 , and the depending member J^4 of the auxiliary entrance D^3 being bifurcated to present a pair of bearing portions j^1 , j^2 , which straddle the upper end of the bracket member J^2 and are arranged in spaced relation thereto. 75

It will now be seen that matrices handled by the upper distributor E will be directed therefrom through the upper magazine entrances D^1 , D^3 , to the upper magazines of the two series, while those handled by the lower distributor E^1 will be directed through the lower magazine entrances D^2 , D^4 , to the lower magazines of the two series. If any one of the four entrances happens to become clogged, or for any other reason an inspection 85 of the magazines or the distributing mechanism is required, one or another or all of the entrances may be swung to the rear about their respective pivotal axes, each being readily accessible and capable of movement 90 independently of the others.

In this type of so-called "mixing machine", it is important that the relation between the entrances and the distributors be undisturbed during the shifting of the magazines for interchange, so that the distribution of matrices may be carried on continuously and in the manner required. For this reason, the magazines (as shown in the Kennedy patent, before referred to) are usually mounted to 100 swing about independent axes located immediately below the corresponding distributors, the entrances moving with the magazines and mounted on the respective magazine base frames. In the present instance, the auxiliary magazines A' , primarily for the sake of economy in manufacture and as shown in Figs. 2 and 3, are likewise mounted to swing about independent axes A^5 , A^6 , the respective base frames thereof being hinged 105 at these points through the medium of short curved arms A^7 , A^8 . It will be observed, however, that while the axis A^6 for the lower auxiliary magazine is located immediately below the lower distributor E^1 , the location 110 of the axis A^5 for the upper auxiliary magazine is remote from the upper distributor E . This particular arrangement is permissible since the upper entrance D^3 is pivoted and sustained independently of the upper auxiliary magazine and its base frame A^2 , the matrix receiving relation of the entrance D^3 to the upper distributor E being thus 115 constantly maintained, irrespective of the swinging movements of the magazine. Under these conditions, a relative movement takes place between the lower end of the magazine entrance D^3 and the entrance end of the upper auxiliary magazine when the latter is swung about its pivotal axis for interchange, but the 120

movement is so slight at this point, due to the proximity thereto of the axis A⁵, that matrices will pass freely over the joint without hesitation.

- 5 The main magazines A, on the other hand, and unlike those shown in the Kennedy patent, are both mounted in a common supporting frame, which consists of the lower magazine base frame A² with its upper extensions A⁴ and the upper main magazine base frame A², which is pivoted to the extensions A⁴ as at a (see Fig. 1). This supporting frame or "shift frame," as it may be called, is mounted at its upper end on trunnions A⁸, whereby it 15 may be swung upwardly and downwardly to bring one or the other of the main magazines A in operative relation to the assembler throat B and the escapement levers C¹. During such swinging movement of the shift frame, the 20 lower ends of the main magazine entrances D¹ and D² (which, as before stated, are carried in the extensions A⁴), are allowed to maintain a fixed close relation to the upper ends of the respective magazines A¹, and consequently, in the distribution of matrix fonts 25 ranging from 5½ pts. to 10 pts., the danger of the thinner and lighter matrices hesitating or becoming lodged at this point of juncture is eliminated.
- 30 The trunnions A⁸, as will be noted from Fig. 1, project laterally from the extensions A⁴ at a level intermediate the levels of the two distributors E, E¹, at the rear thereof, and, for reasons presently to be pointed out, they are 35 mounted in open bearings o formed in the fixed supporting brackets O², there being two of these brackets arranged at opposite sides of the machine clear of the upper magazine entrances, altho only one bracket is shown herein. The particular location of the pivot 40 points thus provided for the shift frame is intended to minimize the movement of the upper ends of the entrances D¹ and D² relatively to the respective distributors E and E¹ during 45 the swinging of the magazines, but further means are provided for causing at such times a bodily shifting of the pivotal axis in order more fully to compensate for such relative movement. The means employed for this 50 purpose (see Figs. 1 and 4) consist of a pair of suspension links O⁶ carried by the fixed brackets O² and connected to the extensions A⁴ so as to control the movement of the shift frame when the latter is swung about the axis A⁸. The arrangement is such that as the 55 magazines are swung downwardly to bring the upper magazine into operative position, the links O⁶ cause the upper rear portion of the shift frame to move bodily upward (as permitted by the open bearings o), and as the magazines are swung upwardly to bring the lower magazine into operative position, the links allow this portion of the frame to move bodily downward in seeking its original position. In this way, by causing the magazine

shift frame to turn about a bodily shiftable axis, the magazine entrances D¹ and D² are maintained in proper matrix receiving relation to the respective distributors E and E¹ at all times, as required.

The swinging of the magazines may be effected by any mechanism suitable for the purpose, the particular mechanism illustrated herein being substantially the same as that used in the commercial linotype machines. 70 This mechanism, which is shown only in connection with the main magazines A, but which may be duplicated for the auxiliary magazines A', consists essentially of a toggle system adapted to raise the shift frame as it is extended and to lower said frame as it is collapsed. In its lowermost position, the shift frame is supported upon a pair of set screws A⁹ (Fig. 1) mounted in the framework and which are adjustable to locate the upper magazine in operative relation to the assembler throat B. In its raised position, the shift frame is supported directly by the toggle system which is so designed that, when straightened out, it will locate the lower 80 magazine in correct registration with the throat B. The toggle system comprises two pairs of links K, K¹, intermediately connected by a transverse rod K², to which the lower members K¹ are fastened and on which the upper members K are loosely mounted. The members K¹ are pivoted at their lower ends in the machine frame, and the members K at their free ends are formed with open bearings or forks k wherein engage pins a³ which project inwardly from lugs a² depending from the lower magazine base frame A². The rod K² is limited in its movements in both directions and when rocked upwardly is stopped 90 just past "dead center" so as to lock the magazines in their raised position. The movement of the rod K² is controlled by a pivoted hand lever K³, whose longer arm extends forwardly within reach of the operator and whose shorter arm K⁴ is connected to the rod K², the arrangement being such that, when the lever is depressed, the rod K² will be rocked forwardly to extend the toggle member and, when raised, will shift the rod rearwardly to collapse the toggles. The shift frame is thus 100 swung upwardly and downwardly to definite positions to bring one or the other of the magazines into operation, as desired.

In order to prevent matrices in the course of distribution from falling into the machine when one or another of the magazine entrances is moved from its active position, automatic devices are provided for tripping the clutch finger G⁸ hereinbefore mentioned. 110 These devices, as will be noted in Figs. 4, 5 and 6, constitute a train of connections carried partly by each of the several magazine entrances D¹, D², D³, and D⁴. In the preferred embodiment illustrated, these connections consist of a pair of horizontally aligned

slide rods J^5 , J^6 supported at their inner ends in the respective bearing portions j^1 , j^2 of the bracket member J^4 of the upper auxiliary entrance D^3 , and at their outer ends in the depending side arms D^6 , D^7 , of said entrance. The slide rod J^5 is extended to the left (according to Fig. 4) through the arm D^6 so as to engage the shorter arm j of the bell-crank lever J , and is provided with a compression spring J^7 , which is seated against the inner side of the arm D^6 and tends constantly to press the rod endwise toward the right. The endwise movement of the rod J^5 , however, is limited in the latter direction by a collar J^8 secured thereto and adapted by the action of the spring J^7 to bank against the bearing portion j^1 of the bracket member J^4 . The slide rod J^6 is likewise limited in its endwise movements by collars J^9 , J^{10} , and normally sustains the rod J^5 toward the left against the tension of the spring J^7 through the medium of a slide J^{11} , being itself sustained by a pivoted dog J^{12} carried by the fixed bracket O^2 . The slide J^{11} is permanently mounted in the upper end of the bracket member J^2 of the lower auxiliary magazine entrance D^4 and is formed at opposite ends with beveled head portions j^3 , j^4 , which are wider than the intermediate portions of the slide and serve to limit its longitudinal movements.

The connections just described complete that part of the train carried by the upper and lower auxiliary magazine entrances and are adapted to cause the release of the trip finger G^8 , and the consequent stoppage of the distributing mechanism, when either of said entrances is swung to the rear from its operative position. If the lower entrance happens to be the one moved, the slide J^{11} is carried away from its position between the rods J^5 and J^6 , and the spring J^7 , in forcing the rod J^5 to the right, relieves the pressure on the bell-crank lever J and thus frees the trip finger G^8 , which may then rock into engagement with the cam G^9 and throw out the clutch. As the entrance is returned to its operative position, the beveled surfaces of the head portions j^3 , j^4 of the slide J^{11} engage the respective rods J^5 , J^6 , and since the rod J^6 is supported against endwise movement toward the right by the dog J^{12} , the rod J^5 will be pushed by the slide J^{11} against the tension of its actuating spring J^7 back to its former position. The bell-crank lever J , by such movement of the rod J^5 , is rocked in a clockwise direction (according to Figs. 5 and 6), and by its engagement with the trip finger G^8 moves the latter out of engagement with the clutch cam G^9 to restart the distributing mechanism.

When the upper auxiliary magazine entrance D^3 is swung backwardly, both slide rods J^5 and J^6 are carried with it, the trip finger G^8 being free to disengage the clutch finger G^1 when the rod J^5 passes out of engagement

with the bell-crank lever J . As the opposite end of the rod J^5 clears the slide J^{11} , the spring J^7 is allowed to push said rod to the right, the collar J^8 in banking against the bracket member J^4 serving to locate the outer end of the rod in proper position to engage the bell-crank lever J when the entrance D^3 is later swung forwardly. At this later time, the inner end of the rod J^5 is adapted to engage the tapered head j^3 of the slide J^{11} and by such engagement the rod is carried endwise to the left and through the lever J disengages the trip finger G^8 from the cam G^9 , the slide J^{11} during this endwise movement of the rod J^5 being sustained by the dog J^{12} through the rod J^6 which has been brought into a position between said dog and the tapered head j^3 of the slide. The end of the shorter arm of the lever J , as well as that of the dog J^{12} , are beveled off so as to facilitate and insure the proper engagement of the respective rods J^5 and J^6 therewith when the entrance D^3 is swung forwardly.

The remaining connections of the train, which are associated with the main magazine entrances D^1 and D^2 , consist of a slide J^{13} mounted in the depending bracket member J^3 of the upper magazine entrance D^1 . This slide is also formed with beveled head portions j^5 , j^6 and is operable by a plate J^{14} , beveled at J^{15} , which is secured to the top surface of the angular bracket member J^1 of the lower main magazine entrance D^2 . Normally, the slide J^{13} abuts against the plate J^{14} (as shown in Figs. 4 and 5) and, in this position, is adapted to sustain the dog J^{12} through an intermediate horizontal rod J^{16} , the latter in order to simplify the construction of adjacent parts (as best shown in Fig. 6) being slidably mounted in the right-hand trunnion A^8 of the main magazine supporting frame. The connection thus established between the entrances D^1 and D^2 and the pivoted dog J^{12} is such that the support for the latter will be instantly taken away when one or the other of said entrances is moved from its operative position, and in either event the spring J^7 is allowed to act as in the case of the entrances D^3 and D^4 to release the trip finger G^8 and stop the distributor.

Fig. 6 illustrates the positions the various parts assume when the lower magazine entrance D^2 is moved rearwardly, the plate J^{14} being shown out of contact with the slide J^{13} and the rods J^5 and J^6 shifted to the right. As the entrance D^2 is pushed home, the beveled surface J^{15} of the plate J^{14} is adapted to engage the slide J^{13} and cam it toward the left, thereby resetting the train and engaging the clutch G^1 in the manner above described. The result is precisely the same when the upper magazine entrance D^1 is moved from and to its operative position, but this time the slide J^{13} is moved relatively to the plate J^{14} and rod J^{16} , so that in the first

instance it is adapted to release the dog J^{12} through said rod, and in the second instance is adapted by the engagement of its beveled surfaces j^5, j^6 with the plate J^{14} and rod J^{16} , respectively, to be cammed by the former toward the left and to push the latter in the same direction.

Having thus described my invention, what I claim is:

1. In a typographical machine, the combination of a plurality of character distributors arranged at different levels and each comprising a toothed bar and a distinct set of matrix conveying screws, a font separator arranged in line with the upper distributor, a plurality of superposed inclined magazines, one for each distributor, assembling devices, a common supporting frame for the magazines pivotally mounted in the machine frame, and means for swinging said frame about its pivotal axis to bring one or another of the magazines into operative relation to the assembling devices without disturbing their connection with the distributors.

2. In a typographical machine, the combination of a plurality of character distributors arranged at different levels and each comprising a toothed bar and a distinct set of matrix conveying screws, a font separator arranged in line with the upper distributor, a plurality of superposed inclined magazines, one for each distributor, assembling devices, a common supporting frame for the magazines pivotally mounted in the machine frame, and means for swinging said frame about its pivotal axis to bring one or another of the magazines into operative relation to the assembling devices, the pivotal axis of said magazine supporting frame being located at a point intermediate the distributors such that the operative connection between the magazines and the respective distributors will be undisturbed during the swinging movement of said frame.

3. In a typographical machine, the combination of two character distributors arranged at different levels and each comprising a toothed bar and a distinct set of matrix conveying screws, a font selecting bridge disposed at the level of the upper distributor, two superposed inclined magazines, one for each distributor, intermediate magazine entrances connecting the magazines with the respective distributors, assembling devices, a supporting frame pivoted at its upper end and wherein the magazines and entrances are mounted, and means for swinging said frame about its pivotal axis to bring either magazine into operative relation to the assembling devices without disturbing the connection of the magazine entrances with the distributors.

4. In a typographical machine, the combination of a plurality of character distributors arranged at different levels and each comprising a toothed bar and a distinct set of

matrix conveying screws, a font separator arranged in line with the upper distributor, a plurality of superposed inclined magazines, one for each distributor, assembling devices, a common supporting frame for the magazines pivotally mounted at its upper end in the machine frame, intermediate magazine entrances carried by said frame, means for swinging the frame about its pivotal axis to bring one or another of the magazines into operative relation to the assembling devices, and means for shifting the pivotal axis of the supporting frame during the swinging movement thereof so as to maintain the operative relation of the magazine entrances to the distributors.

5. In a typographical machine, the combination of two character distributors arranged at different levels and each comprising a toothed bar and a distinct set of matrix conveying screws, a font separator arranged at the level of the upper distributor and serving to direct matrices of one font directly onto the upper distributor bar and deliver matrices of other fonts to the lower distributor, two superposed inclined magazines arranged in operative relation to the distributors, assembling devices, a pivoted supporting frame common to both magazines and movable about its pivotal axis to locate either magazine in operative relation to the assembling devices, and a pair of intermediate magazine entrances, one for conducting the matrices from the upper distributor to the upper magazine, and the other for conducting matrices from the lower distributor to the lower magazine, said entrances being mounted in said supporting frame so that either may be moved, without disturbing the other, rearwardly and downwardly to give access to the interior parts when desired.

6. In a typographical machine, the combination of two character distributors arranged at different levels and each comprising a toothed bar and a distinct set of matrix conveying screws, a font separator arranged at the level of the upper distributor and serving to direct matrices of one font directly onto the upper distributor bar and deliver matrices of other fonts to the lower distributor, two superposed inclined magazines pivotally mounted at their upper ends, assembling devices, a pair of intermediate magazine entrances, one for conducting the matrices from the upper distributor to the upper magazine and the other for conducting matrices from the lower distributor to the lower magazine, and means for swinging the magazines about their pivotal axes to locate either in operative relation to the assembling devices without disturbing their connections with the respective distributors, the upper magazine entrance being mounted so that it may be moved bodily rearward between the distributors to give access to the interior parts.

7. In a typographical machine, the combination of two character distributors arranged at different levels and each comprising a toothed bar and a distinct set of matrix conveying screws, a font separator arranged at the level of the upper distributor and serving to direct matrices of one font directly onto the upper distributor bar and deliver matrices of other fonts to the lower distributor, two superposed inclined magazines arranged in operative relation to the distributors, assembling devices, a pivoted supporting frame common to both magazines and movable about its pivotal axis to locate either magazine in operative relation to the assembling devices, and a pair of intermediate magazine entrances pivotally mounted in said frame, one for conducting the matrices from the upper distributor to the upper magazine and the other for conducting matrices from the lower distributor to the lower magazine, said upper magazine entrance being movable bodily rearward about its pivotal axis in a path between the distributors to give access to the interior parts.
8. In a typographical machine, the combination of two character distributors arranged at different levels and each comprising a toothed bar and a distinct set of matrix conveying screws, two superposed inclined magazines, one for each distributor, and a pair of intermediate magazine entrances connecting the upper and lower magazines with the upper and lower distributors respectively, the lower magazine entrance being pivotally mounted and arranged to swing in a path below the distributors, and the upper magazine entrance being mounted for a bodily movement in a path between the distributors.
9. In a typographical machine, the combination of two character distributors arranged at different levels and each comprising a toothed bar and a distinct set of matrix conveying screws, two superposed inclined magazines, one for each distributor, a pair of intermediate magazine entrances connecting the upper and lower magazines with the upper and lower distributors respectively, the upper magazine entrance being mounted so that it may be swung between the distributors rearwardly and downwardly to an inverted position, and a tray or receptacle carried by said entrance and adapted at such time to assume a position beneath the inverted upper end of the entrance.
10. In a typographical machine, the combination of two character distributors arranged at different levels, one directly above the other, two superposed inclined magazines, a pair of magazine entrances connecting the upper and lower magazines with the upper and lower distributors respectively, a supporting frame hinged at its upper end and wherein the magazines and entrances are mounted, the latter being movable independ-

ently toward the rear for access to the interior parts, means for swinging said frame about its pivotal axis to bring either of the magazines into operative position without disturbing their connection with the respective distributors, a clutch through which the distributors are operated, and a train of connections carried partly by one and partly by the other magazine entrance for controlling the operation of the clutch, whereby the movement of either of the magazine entrances from operative position will disengage the clutch and stop the distributors.

11. In a typographical machine, the combination of two constantly operated character distributors, two superposed inclined magazines, a pair of intermediate magazine entrances, one for conducting the matrices from the upper distributor to the upper magazine and the other for conducting matrices from the lower distributor to the lower magazine, the said entrances being independently mounted and each movable toward the rear for access to the interior parts without disturbing the other, the upper magazine entrance being adapted to move in a path between the distributors and the lower magazine entrance in a path below the distributors, a clutch through which the distributors are operated, and a train of connections carried partly by each one of the magazine entrances for controlling the operation of said clutch, whereby the movement of one or the other of said entrances from operative position will disengage the clutch and stop the distributors.

12. In a typographical machine, the combination of two main character distributors arranged at different levels and each comprising a toothed bar and a set of matrix conveying screws, two superposed inclined magazines, a pair of intermediate magazine entrances, one for conducting the matrices from the upper distributor to the upper magazine and the other for conducting matrices from the lower distributor to the lower magazine, the said entrances being independently mounted and each movable rearwardly and downwardly for access to the interior parts without disturbing the other, means for driving the distributor screws, and a train of connections carried partly by the upper magazine entrance and partly by the lower magazine entrance for controlling the operation of said driving means, whereby the movement of either entrance from its operative position will break the controlling connections and stop the distributing mechanism.

13. In a typographical machine, the combination of two character distributors comprising a toothed bar and a distinct set of matrix conveying screws, two series of superposed magazines arranged side by side, magazine entrances connecting the magazines of

each series with the respective distributors and mounted so as to be movable independently rearwardly and downwardly for access to the interior parts, a clutch through which the distributors are operated, and a train of connections carried partly by each of the several magazine entrances for controlling the operation of the clutch, whereby the movement of one or another of said entrances from operative position will disengage the clutch and stop the distributing mechanism.

14. In a typographical machine, the combination of a distributing mechanism, two series of superposed magazines arranged side by side, separate magazine entrances connecting the respective magazines of each series with the distributing mechanism and mounted so as to be movable independently rearwardly and downwardly for access to the interior parts, a clutch through which the distributing mechanism is operated, and a train of connections carried partly by each one of the magazine entrances for controlling the operation of the clutch, whereby the movement of one or another of said entrances from operative position will disengage the clutch and stop the distributing mechanism.

15. In a typographical machine, the combination of two character distributors arranged one above the other with a space between them, two inclined magazines, and intermediate magazine entrances for conducting matrices from the distributors to the respective magazines, the upper magazine entrance being mounted to turn on a fixed axis located at the rear of the two distributors and in such position that it may be moved bodily rearward over the lower distributor without interfering with the upper distributor.

16. In a typographical machine, the combination of two character distributors arranged at different levels and each comprising a toothed bar and a distinct set of matrix conveying screws, a pair of superposed inclined main magazines, intermediate magazine entrances connecting the magazines with the respective distributors, a common shift frame for the magazines wherein the entrances are also mounted, said frame being pivoted at its upper end on an axis so located that either magazine may be brought into operative position without disturbing the connection of the entrances with the corresponding distributors, a second pair of superposed inclined auxiliary magazines arranged at the side of or in tandem to the first pair of magazines and pivotally mounted at their upper ends on independent axes to permit either magazine to be swung into operative position, and intermediate magazine entrances for connecting the auxiliary magazines with the respective distributors, one of the latter entrances being pivoted to the machine frame and the axis of the magazine as-

sociated therewith being located adjacent the lower end of said entrance so that the operative connection between the entrance and magazine will be preserved during the swinging of the magazines for interchange.

17. In a typographical machine, the combination of two character distributors arranged at different levels and each comprising a toothed bar and a distinct set of matrix conveying screws, a pair of superposed main magazines, intermediate magazine entrances connecting the magazines with the respective distributors, a common shift frame for the magazines and wherein the entrances are also mounted, said frame being pivoted at its upper end on an axis so located that either magazine may be brought into operative position without disturbing the connection of the entrances with the distributors, a pair of superposed inclined auxiliary magazines arranged at the side of or in tandem to the main magazines and mounted on separate base frames pivoted at their upper ends on independent axes to permit either magazine to be swung into operative position, and intermediate magazine entrances, one carried in the machine frame and connecting the upper auxiliary magazine with the upper distributor, and the other carried by the lower magazine base frame and connecting the lower magazine with the lower distributor, the pivotal axis for the upper auxiliary magazine being located adjacent the lower end of the associated magazine entrance, and the pivotal axis for the lower auxiliary magazine being located immediately below the lower distributor, so that the operative connections of said auxiliary magazines with the distributors will be maintained when they are swung upwardly and downwardly for interchange.

In testimony whereof, this specification has been duly signed by

JOHN R. ROGERS.
